UNITED STATES PATENT OFFICE.

ERNEST MANGEON, OF PARIS, FRANCE.

IMPROVEMENT IN PRIVY-SEATS.

Specification forming part of Letters Patent No. 59,150, dated October 23, 1866.

To all whom it may concern:

Be it known that I, ERNEST MANGEON, of Paris, in the Empire of France, have invented certain new and useful Improvements in Privy-Seats; and I do hereby declare that the following is a full, clear, and exact description of the same, reference being had to the accompanying drawings, making a part of this specification, in which—

Figure 1 is a vertical transverse section, taken in the line xx of Fig. 3, and showing the privy-seat in a closed condition. Fig. 2 is a vertical transverse section taken in the line yy of Fig. 3, and representing the privy-seat in an open condition. Fig. 3 is a plan or top view, also representing the privy-seat in an open condition.

Similar letters of reference indicate corresponding parts in all the figures.

It is desirable in water-closets or privies situated where a scarcity of water exists that some means other than repeated washings be employed to prevent the escape from the privy of the noxious gases or emanations engendered by the contents thereof, and that the privy should be so constructed that it may be easily and conveniently cleaned or purified when desired.

This invention is designed to accomplish these results; and it consists in a novel means of securing an air-tight joint between the hopper or casing of the privy and the cover thereof when the said cover is closed, and also in the employment of a valve so combined with the said cover and with the hopper or casing that when the cover is raised the valve will close the bottom of the said hopper, and thus prevent the escape of gases from the vault or receptacle underneath the same, and when the said cover is closed the valve will be tilted to drop the impurities deposited thereon into the receptacle just mentioned; the invention being adapted to privies having seats of different kinds, and also to chamber-stools provided with removable vessels or receptacles underneath their seats, and its construction being such that it may be washed out and cleansed when desired by a small quantity of water, and with very little trouble.

To enable others to understand the construction and operation of my invention, I will pro-

ceed to describe it with reference to the drawings.

The invention is shown in the drawings as applied to that variety of water-closets known in the French language as the "Siége à la Turque."

A indicates a casing or hopper, which constitutes the upper portion of the apparatus, and which has projecting downward from its rear-most part a rectangular or other suitably-shaped rim, a , by means of which it is fitted upon the enlarged upper end of the conduit pipe or passage B, which communicates with a suitable vault or receptacle below. The forward part of the hopper is furnished with a flat bottom, b , on which the person using the apparatus stands while so doing. The rearmost part of the said hopper is open at the bottom, as shown at A' , the said opening being surrounded by a downwardly-projecting flange or rim, c , which projects downward into the flange B, and has fitted upon its lower end another annular rim, d , as shown more clearly in Fig. 2. The lower end of this last-mentioned rim d is closed by a valve, C, which is secured upon a transverse pivot, a' , working in suitable bearings formed at opposite sides and upon the lower edge of the said rim d .

The top or upper edge of the casing or hopper A is formed with an outwardly-projecting rim, e , extending entirely around it and curved in its cross-section in such manner as to form an annular groove or channel, B', in the said upper edge or top of the casing. This channel is filled with water, mercury, or other suitable liquid, in order to form an air-tight joint between the casing and the lid or cover thereof, as will be presently fully set forth.

D represents the lid or cover of the apparatus, which is hinged to the rearmost side of the casing A, as shown at f . When this cover is closed its edge fits snugly upon the outer edge of the rim e , as shown at e' in Fig. 1, and situated at a suitable distance within the said edge of the cover is a downwardly-projecting annular rim, D' , which extends down into the channel B' near the innermost side thereof, and below the surface of the liquid contained therein, as represented in the said Fig. 1, so that the liquid effectually seals the joint between the casing and the cover, and thus prevents

the escape of gaseous emanations from the said casing or hopper A, when the cover thereof is closed, as just herein fully set forth, while the edge e' of the cover, covering the liquid in the channel B', prevents the accidental displacement of the same.

Similar means may be employed, if desired, for forming an air-tight joint between the flange a of the casing A and the upper end of the conduit pipe or passage B, as shown at g in Figs. 1 and 2.

Secured upon each end of the pivot a' of the valve C is a slotted arm, m, and sliding in suitable bearings attached to the inner side of the back of the casing A, near the end thereof, is a vertical rod, n, the lower end of which is curved, as shown in dotted lines in Fig. 2, and is attached to the slotted arm by means of a pin, n', passing transversely through the slot in the said arm.

The upper end of each sliding rod n is connected with the hinged cover D by means of a connecting-rod or pitman, r, in such manner that when the cover is raised up the slotted arm m will be lifted so as to bring the valve C into a horizontal position to close the opening A', as shown in Figs. 2 and 3, and thus prevent the escape of offensive odors or noxious gases from the passage B. It should be mentioned here that the forward side of the lower edge of the rim d is curved inward and upward, so as to form a shallow trough, d', in which the forward edge of the valve fits when the same is closed, and that the rearmost edge of the valve is also turned upward to form a similar trough, into which the rear edge of the said rim fits, as at d''. The said trough, being filled with water, effectually seals the joint be-

tween the front and rear edges of the valve and the adjacent edges of the rim d, when the valve is closed, as just set forth. When the said cover is turned down in closing the casing, as hereinbefore explained, the slotted arm m will be pushed downward and turn the valve C, attached thereto, into a vertical position, as shown in Fig. 1, thus unclosing the opening A' and allowing the impurities deposited upon the valve, when the cover D is raised to allow the apparatus to be used, to fall through the said opening into the conduit pipe or passage B, and thence into the vault below. By these means the escape from the privy of gases or of noxious and offensive odors is effectually prevented, not only when the apparatus is closed, but also when it is opened for use. Furthermore, the invention may be applied, when desired, to water-closets having seats of any suitable kind, and also to chamber-stools provided with vessels or receptacles underneath their seats.

What I claim as new, and desire to secure by Letters Patent, is—

The combination of the cover D, valve C, and mechanism by which the position of the cover controls the position of the valve, so that when either is open the other is closed, all being arranged, in connection with the hopper A and conduit-pipe B of a water-closet or privy, substantially as herein set forth.

In testimony whereof I have signed my name to this specification before two subscribing witnesses.

E. MANGEON.
